UNITED STATES PATENT OFFICE

JAMES J. McGERRY, OF GRAND RAPIDS, AND CHARLES H. WHITING, OF KALAMAZOO, MICHIGAN, ASSIGNEES TO ROTARY UTILITY CORPORATION, OF CHICAGO, ILLINOIS, A CORPORATION OF ILLINOIS

DESIGN FOR A CHAIR

Application filed July 18, 1930. Serial No. 36,392. Term of patent 7 years.

To all whom it may concern:

Be it known that we, JAMES J. McGERRY, a citizen of the United States, residing at Grand Rapids, in the county of Kent and State of Michigan, and CHARLES H. WHITING, a citizen of the United States, residing at the city and county of Kalamazoo, State of Michigan, have invented a new, original, and ornamental Design for Chair, of which the following is a specification, reference being had to the accompanying drawing, forming part thereof.

Fig. 1 is a front view, and

Fig. 2 is a side view of a chair showing our new design.

We claim:

The ornamental design for a chair, as shown.

JAMES J. McGERRY.
CHARLES H. WHITING.
